UNITED STATES PATENT OFFICE.

STANLEY CUROL, OF WILLIMANTIC, CONNECTICUT.

DESIGN FOR A BRACKET FOR A CURTAIN AND SHADE ROLLER.

51,719.

Specification for Design.

Patented Feb. 5, 1918.

Application filed November 10, 1916. Serial No. 130,651. Term of patent 7 years.

To all whom it may concern:

Be it known that I, STANLEY CUROL, a subject of the King of Hungary, residing at Willimantic, in the county of Windham and State of Connecticut, have invented a new, original, and ornamental Design for a Bracket for a Curtain and Shade Roller, of which the following is a specification, reference being had to the accompanying drawing, forming part thereof.

The figure is a view in perspective of a bracket for a curtain and shade roller, showing my new design.

I claim:—

The ornamental design for a bracket for a curtain and shade roller, as shown.

STANLEY CUROL.
